UNITED STATES PATENT OFFICE

155,685

DESIGN FOR A TUBE EXTRACTOR

Otis C. Currie, Jackson, Mich., assignor to K & M Products Company, Jackson, Mich.

Application July 12, 1946, Serial No. 131,542

Term of patent 14 years

(Cl. D54—13)

To all whom it may concern:

Be it known that I, Otis C. Currie, a citizen of the United States, residing at Jackson, in the county of Jackson and State of Michigan, whose post-office address is C/O K & M Products Company of Jackson, Michigan, have invented a new, original, and ornamental Design for a Tube Extractor, of which the following is a specification, reference being had to the accompanying drawing, forming part thereof.

Fig. 1 is a side elevational view of the tube extractor, according to my new design.

Fig. 2 is an elevational view taken at a right angle to Fig. 1.

What I claim is:

The ornamental design for a tube extractor, substantially as shown.

OTIS C. CURRIE.
